WINDOW LOCK STRUCTURE

Joel Henry Hendrix, New Castle, Pa.

Application July 30, 1932, Serial No. 626,893

8 Claims. (Cl. 70—29)

Generically this invention relates to lock structures, but it more specially is directed to the type adapted for use in conjunction with a rack.

The principal object of this invention is the provision of a lock of this character having yieldable contact members adapted to travel over said rack and bolt means associated therewith operable to secure said lock at any desired point with respect to said rack.

10 Another object of this invention is the provision of a lock structure of this character more especially adapted for cooperation with a rack, and comprising a movable bolt and a pair of bolt supporting cam latch jaws associated therewith, said jaws and bolt being yieldably movable as a unit to permit the lock to travel over said rack, said bolt being additionally movable with respect to said jaws to locked and unlocked positions.

15 A further object of this invention is the provision of a lock of this character applicable to windows and the like comprising a nested jaw and bolt structure mounted and movable as a unit adapted to automatically engage a selected notch or slot in a rack to maintain the window at such point, but yieldingly operable upon manual movement of the window to retracted position, said bolt being independently movable with respect to said jaws to lockingly engage such selected slot, and means operable in a single direction for effecting movement of said bolt to locking and unlocking positions with respect to said rack.

20 With these and other objects in view, which will become apparent as the description proceeds, the invention resides in the construction, combination and arrangement of parts, hereinafter more fully described and claimed, and illustrated in the accompanying drawing, in which like characters of reference indicate like parts throughout the several figures; of which:

25 Fig. 1 is a fragmentary front elevation of a window structure with parts broken away showing the bolt in locking position;

30 Fig. 2 is a side elevation with the cover plate removed and showing the bolt in extended position;

35 Fig. 3 is similar to Fig. 2 with the bolt in retracted or unlocked position;

40 Fig. 4 is a cross section taken on the line 4—4 of Fig. 2;

45 Fig. 5 is detail perspective view of the bolt trigger member;

50 Fig. 6 is a fragmentary perspective view of the key; and

55 Fig. 7 is a fragmentary perspective view of the rack member.

The devices of this general character with which I am familiar have proven deficient, by reason of complex arrangement, costly construction, inability to automatically assume operative and inoperative window sash supporting positions by manual movement of the sash in either direction, nonprovision of means for locking the sash at any desired point within its range of movement, and in lieu of the cord and weights now prevalent, and it was to overcome such deficiencies by providing a lock structure adapted to cooperate with a fixed rack to maintain the window sash at any desired point without the aid of sash weights, if desired, comprising a yieldable normally extended latch cam jaw and locking bolt structure adapted to selectively engage complementary notch openings in the rack and be disengaged therefrom by manual movement of the sash, said jaws and bolt being normally movable as a unit, said bolt being additionally movable with respect to said jaws to locking and unlocking positions, by a key operable in one direction, that I designed the device forming the subject matter of this invention.

In the illustrated embodiment characterizing this invention there is shown a lock structure A, rack B, window frame C, and movable window sash D.

The lock A comprises a casing including side section 1, top and bottom sections 2 and 3, respectively, rear wall section 4, removable side section 5 constituting a cover, and end face plate 6 terminating at its ends in projections 7 and at its side edges in lateral flanges 8 extending beyond the sides 1 and 5. The face plate 6 is formed with a central opening 9 and with inwardly projecting lugs 10 forming continuations of the top and bottom end walls of said opening to form guide seats for one end of the latch jaw and bolt mechanism E slidably mounted in said opening. The other end of said mechanism is similarly mounted between the spaced lugs 11 formed on rear wall section 4 in alignment with lugs 10. One of said lugs 11 is formed with an enlarged portion 12 formed with a threaded opening 13 and terminating in a fulcrum point 14 for a purpose hereinafter more fully appearing.

The latch jaw mechanism E slidably mounted between the lugs 10—11 includes the latch bar 15 substantially rectangular in general contour formed at one end with the thickened spaced latch jaws 16 and 17 having inclined oppositely extending cam faces 18. Jaw member 17 is formed with a depending stop lug 19 adapted to engage lug 10 and limit the forward movement

of said bar 15. The lower edge of said bar 15 is formed with a cut out portion 20 extending to a point substantially central thereof and a cut out portion 21 intermediate said jaws for 5 purposes directly more fully appearing. The other end of said bar 15 adjacent its corners is formed with thickened portions 22 similar in thickness and spaced relation to jaws 16 and 17, forming seat 23 extending between the respective 10 jaws and portions 22, the free ends of the latter being slidably engageable with the respective guide lugs 11 as will be clear without further description.

A lock bolt 24 is positioned on said seat 23 15 slidable with respect to latch bar 15, and is formed at one end with a thick head portion 25 forming on each side of the bolt a shoulder 26. One surface of said head extends in cut out portion 21, the shoulder 26 limiting the movement 20 of said bolt 24 in unlocking direction, and stop lug 27 formed on one edge of said bolt and engageable with jaw 16 limits the movement of said bolt in locking direction. Said bolt is formed at its rear end with a raised portion 28 and 25 spaced therefrom is a lateral finger 29 formed with a cam surface 30 and adjacent thereto the edge of said bolt is cut out as at 31 for a purpose hereinafter appearing.

Spaced inwardly from portion 28 is lug 32 on 30 which one end of trigger member 33 is rotatably mounted. Said trigger is formed on one edge spaced from its free end with a lateral projection 34 terminating in a stop lug 35 adapted to limit the movement of said member in one direction, and is formed on its opposite edge with lug 36 engagable with the edge 37 of jaw 17 to normally maintain bolt 24 in retracted position as will hereinafter more fully appear.

Mechanism E mounted as above described is 40 normally maintaining in extended position by spring 38 threaded over the spaced lugs 39 of raised portion 40 formed on the inner surface of side 1, and under knob 41 formed on the inner surface of top section 2 intermediate said lugs 45 39, which tends to exert a spreading force on spring 40, one end of which engages lug 34 and the other engages fulcrum point 14 and behind lug 42 formed on latch bar 15.

Suitably located in the side 1 intermediate 50 the lowermost lugs 10 and 11 is a key receiving opening 44 corresponding to the configuration of ward portion 45 of key 46. When the bolt 24 is in retracted position, as shown in Fig. 3, operation of key 46 to the right causes 55 ward or bit 45 to engage and lift trigger 33 disengaging lug 36 from seat 37, and spring 38 seatting against lug 34 moves bolt 24 to extended or locked position as shown in Fig. 2. Further movement of ward 45 in the same direction causes it 60 to engage cam surface 30 of finger 29 retracting bolt 24 until lug 36 again engages seat 37 under the action of spring 38 maintaining the bolt in such retracted position, and whereupon mechanism E may be retractively controlled as a unit 65 by spring 38 acting on lugs 34 and 14 as and for a purpose hereinafter more fully appearing.

The side or cover 5 is formed with a similar opening or key hole 44 and is secured to the casing by suitable screws engaging threaded opening 47 70 in lug 48 formed on bottom section 3, and similar opening 13 in portion 12, as will be clear without further discussion.

The lock A is adapted to be embedded in a window sash frame or the like in a manner well 75 known to the art as shown in dotted outlines in

Fig. 1, and in position for coacting engagement with rack B now to be described.

Rack B is adapted to be suitably secured by screws or otherwise to or embedded in one surface of window frame C so that surface 49 will 80 slidably contact the contiguous surface of the sash D and face plate 6 embedded therein, and is formed with a plurality of spaced slots or notch openings 50 corresponding in configuration to the bolt head 25 and having horizontal walls 51, the end walls inclining upwardly therefrom to form the bevel or cam surface 52 corresponding to the complementary cam surface 18 of the latch jaws 16-17 of the bar 15 which they are adapted to contactingly engage when said bar is in extended 90 position, as clearly shown in Fig. 1 of the drawing.

While the key controlled operation of the bolt 24 is thought to be clear from the above description, it might be well to further describe the operation of the latch mechanism E.

As above shown, when the bolt 24 is locked in retracted position a unitary slidable latch structure is effected. Normally such structure is maintained in extended position in engagement with a desired notch 50, the force of the combined 100 spring and the coacting engagement of the complementary cam faces of the jaws and rack being sufficient to maintain the window sash at any desired point within its range of movement, said cam construction adapted to effect retraction of 105 said latch structure from said notch or notches upon manual force being applied to said sash in either direction and automatically engaging the next or desired notch to hold the window sash as in the first instance. All that is necessary to lock 110 the sash in such position is to insert and turn the key 46 operating ward 45 to lift trigger 33 releasing bolt 24 which is projected into locking engagement with its keeper or rack by the additional action of the spring and which in conjunction with 115 jaws 16-17 effects a rigid locking bolt unit effectually locking the sash against movement in either direction or in closed position as will be apparent without further explanation.

While I have preferably shown the lock as applied to the sash, it will be understood that the parts may be reversed, that is, the lock mounted in the frame according to the exigencies of the particular requirements without departing from the principles of the invention.

It will be apparent from the foregoing that I have provided a simple and unique lock structure, easily installable, manufacturable at a minimum of cost, and efficient for the purposes intended.

Although in practice I have found that the form 130 of my invention illustrated in the accompanying drawing and referred to in the above description as the preferred embodiment is the most efficient and practical; yet realizing the conditions concurrent with the adoption of my invention will 135 necessarily vary, I desire to emphasize that various minor changes in details of construction, proportion and arrangement of parts, may be resorted to within the scope of the appended claims without departing from or sacrificing any of the 140 principles of this invention.

Having thus described my invention, what I desire protected by Letters Patent is as set forth in the following claims:

1. A lock comprising a slidable latch jaw 145 structure, a bolt slideable with said jaw structure but susceptible of independent movement with respect thereto, a trigger member associated with the bolt normally maintaining the bolt in fixed position with respect to said latch jaws, said trig- 150

ger and bolt being adapted to be moved to locked and unlocked positions by a key.

2. A lock comprising a slideable latch jaw structure, a retractile bolt slideable with the latch jaw structure but susceptible of independent movement with respect thereto, a trigger carried by the bolt engageable with the latch jaw structure, means normally holding the trigger in engagement with the latch jaw structure and operable upon disengagement of the trigger to move the bolt to extended position, said trigger adapted to be tripped and said bolt retracted by a key.

3. A lock comprising a slideable latch bar including spaced jaws, a bolt movable as a unit with the latch jaws but susceptible of independent movement with respect thereto to locked and unlocked positions, trigger means associated with said bolt, said trigger and bolt adapted to be operated by a key operable in a single direction to trip the trigger and retract the bolt.

4. A lock for windows and the like comprising a retractile latch element including a cam jaw means normally in window supporting engagement with a keeper, and automatically retractile from such engagement upon movement of the window in either direction, slideable bolt means associated with said jaw means, adapted to engage said keeper, a trigger member carried by said bolt, said trigger adapted to be engaged by a key for effecting movement of said bolt to locking and unlocking positions with respect to said keeper.

5. A lock for windows and the like adapted to engage a rack, comprising a slideable latch bar including spaced jaws normally maintained in extended engagement with the rack, cam means associated with said jaws for effecting retractile disengagement thereof from said rack

upon movement of the window in either direction, a slideable bolt associated with said latch jaws, a trigger member carried by said bolt, and means coacting with said trigger to normally maintain the bolt in unlocked position but operable to lock said latch jaws in fixed engagement with said rack.

6. A lock for windows and the like adapted for engagement with a rack comprising integrally connected slideable latch jaws including a bolt normally movable as a unit with said latch jaws, yieldable means normally maintaining the latch jaws in engagement with said rack, and cam means carried by said latch jaws to effect retraction thereof upon force being applied to said window in either direction.

7. A lock for windows and the like adapted for engagement with a rack comprising slideable latch jaws, spring means normally maintaining the latch jaws in extended position, a retractile bolt slideable with the latch jaws but susceptible of independent movement with respect thereto, a trigger connected to said bolt normally maintaining the same in retracted position, said spring additionally holding the trigger in bolt retracted position and acting upon release of the trigger to move the bolt to locking position.

8. A lock comprising a slideable latch bar including spaced latch jaws, a latch bolt slidably carried by the bar and normally constituting with said jaws a slideable latch unit but susceptible of independent movement with respect to said jaws, a trigger carried by said bolt, yieldable means normally holding said trigger in bolt retracted position but operable upon release of said trigger to move the bolt to extended position.
